UNITED STATES PATENT OFFICE.

WILLIAM GENTRY SHELTON, OF NEW YORK, N. Y.

TALKING-MACHINE MOTOR.

1,289,262.

Specification of Letters Patent. Patented Dec. 31, 1918.

Application filed March 16, 1918. Serial No. 222,833.

To all whom it may concern:

Be it known that I, WILLIAM GENTRY SHELTON, a citizen of the United States of America, residing in the borough of Manhattan, city of New York, county of New York, and State of New York, have invented certain new and useful Improvements in Talking-Machine Motors, of which the following is a specification.

10 This invention relates to improved electrical apparatus for operating talking machine reproducers and has for an object to provide means for automatically stopping the motor and breaking the circuit thereof after a pre-
15 determined amount of rotation is imparted to the record supporting device, and also to provide means for setting the cutting off mechanism at a predetermined point and by the said operation closing the circuit for
20 starting the motor.

In the drawings accompanying this application two modifications of a practicable embodiment of my invention are illustrated, in which drawings:—

25 Figure 1 shows a form of my improved apparatus, in elevation, a portion of the motor casing being broken away to show the relative position of the parts.

Fig. 2 is a horizontal section of Fig. 1, 30 taken on a plane at about the line 2—2, looking downwardly.

Fig. 3 is a top view of the motor showing the permutation index.

Fig. 4 is a view somewhat similar to Fig. 35 1, showing a different arrangement of the reducing gear, and

Fig. 5 is a top view of the Fig. 4 construction.

In the constructional embodiment illustrated in Figs. 1, 2 and 3, a form of motor casing is illustrated for resting upon some portion, preferably the table of a talking machine. This casing is designated by the reference character 7. Within the casing is 40 shown mounted the armature 8 of an electric motor. The shaft 9 thereof being shown provided at its lower end with a friction pulley 10 for engaging the record support or turntable 11 adapted to carry a record 45 disk 12.

One of the objects of this invention is to provide means whereby the operator upon starting the motor may set a circuit breaker in position to stop the motor and the rotation of the record disk upon a predetermined amount of rotation thereof, either

based upon the diameter of the disk itself, or based upon such diameter rectified by the quantity of record carried by the disk. To this end the armature shaft 9 during its rotation of the record support 11 also operates through the instrumentality of reduction gearing a circuit breaker. In the present illustration it is assumed that the current is led into the motor by means of a suitable cord 13 and that such current passes to the switch fingers 14 and 15, which are shown mounted one above the other, and properly insulated. The circuit is normally closed by the engagement of such fingers one with the other, and is interrupted by the forcing of these fingers apart by a circuit breaker formed of insulation material. Such current breaker being illustrated at 16 in the form of an arm fast on a shaft 17 projecting above 75 the top plate 18 of the motor casing, other parts of the mechanism heretofore mentioned being located below such top plate. The outward portion of the shaft 17 is shown having fast upon it a finger 19 adapted to 80 register with an index 20 suitably carried by the top plate. The end of the shaft 17 is shown finished off by means of knurled head 21, for enabling the ready setting of the switch. The upper end of the armature 85 shaft 9 is shown provided with a worm 21 meshing with a worm wheel 22 fast on a shaft 23 supported in suitable bearings carried by the casing. A worm 24 is formed on the shaft 23 and is shown meshing with a 90 worm wheel 25, frictionally carried by the shaft 17. The reductions which I have found useful in practice are approximately 10 to 1 between the pulley 10 and the record support 11, 30 to 1 between the worm 21 and the 95 worm wheel 22, and 120 to 1 between the worm 24 and the worm wheel 25. This of course is given merely by way of illustration for the purpose of explaining to the skilled workman the principle of operation of the 100 mechanism in the example shown in the drawings.

The index 20, as shown in Fig. 3, is provided with a point marked "Off" which indicates, when the finger 19 registers therewith, that the armature 16 is interposed between the switch fingers 14 and 15 and that the current is off. The index or dial 20 is also provided with points marked "6", "10" and "12", intended to correspond with record 110 disks of six, ten and twelve inch diameters respectively, and located at distances apart,

which correspond with the travel of the indicating finger 19, and the switch arm 16 during the time the motor rotates a record disk corresponding to one of such indications 5 through the normal amount of rotation required for reproducing a record of that diameter.

Although the operation is quite obvious from the foregoing detailed description, yet 10 it may be well to state that upon placing the record disk 12 on the support 11, the operator will notice the diameter of the disk and take hold of the knurled head 21 and turn the pointer 19 until it registers with the indication on the dial corresponding with the diameter of the record. This movement not only determines the amount of travel of the switch arm 16 before it interrupts the circuit, but also immediately closes such circuit and starts the motor. After the operator becomes more skilful in gaging the amount or quantity of record upon the disk, he places the pointer either short of or beyond the point indicated for the diameter 25 of the record which he is employing according as the disk contains less or more record than is normal for that diameter. It is also feasible for the operator to arrange the device so that it will interrupt the circuit and 30 stop the record at any intermediate point, so that if he does not wish to have the end of the record reproduced, he may set the device for stopping the motor wherever he wishes. It is, of course, apparent that the 35 reduction gearing immediately upon the setting of the switch arm 16 moves this toward the fingers 14, 15 and at the predetermined point causes such arm 16 to interpose itself between such fingers and interrupt the current.

The eccentric relation of the dial 20 to the top plate 18 for certain classes of trade is undesirable owing to its unsymmetrical appearance. The form of mechanism illustrated in Figs. 4 and 5 shows the dial 200 formed concentrically upon the top plate 180 and the shaft 170 in axial alinement with the armature shaft 90. The reduction gear in this instance comprises a worm 210 on the shaft 90 meshing with a worm wheel 220 fast on shaft 230, such shaft having a worm meshing with a worm wheel 250 fast on a shaft 251, which shaft also has fast upon it a friction gear 252, engaging the periphery of a disk 253 fast on the shaft 170. The insulation switch arm 160 is shown carried by the disk 253, the switch fingers 140 and 150 in this instance being carried by the top plate 180 of the casing. The index finger 190 is shown traversing a circle concentric with the outline of the motor casing and the setting head 210 as symmetrically located thereon.

In the Fig. 1 construction the necessary 65 slipping of the parts in setting is permitted

by the frictional mounting of the gear wheel 25 upon the shaft 17. In the Fig. 4 construction the slipping takes place between the disk 253 and the friction pulley 252.

It is, of course, obvious that various 70 changes in structure may be made, as occasion may demand, within the scope of the claims, without departing from the spirit of the invention, and that the examples of the invention shown in the drawing are by way 75 of illustration.

What I claim is:—

1. The combination with a talking-machine record turn-table, of an electric motor for driving the same, a switch for controlling the motor circuit and embodying a settable member movable to variable positions on starting, indicating means therefor, and reduction gearing between the motor shaft and such settable member. 85

2. The combination with a talking-machine record turn-table of an electric motor for driving the same, a switch for controlling the motor circuit and embodying a settable member and reduction gearing between the motor shaft and such settable member, a dial, and an index pointer movable with the settable member. 90

3. A talking-machine motor comprising an electric motor having a pulley for driving the record of a talking-machine, a switch for the motor circuit, a member adapted to open and close such switch, reduction gearing between the motor shaft and the said member, and means for moving the said member away from its circuit breaking position a predetermined distance for permitting a predetermined amount of rotation of the said pulley. 95

4. A talking-machine motor comprising 105 an electric motor, and means carried thereby for driving a talking-machine record, a switch for the circuit of said motor comprising a pair of spring fingers, an insulation arm adapted for interposition between 110 said fingers, a shaft carrying the switch arm, and reduction gearing between the said shaft and the motor shaft, with a slipping connection between the latter and said arm.

5. A talking-machine motor as set forth 115 in claim 4 embodying a dial on the motor casing and an index finger registering with such dial and carried by the switch arm shaft.

6. A talking-machine motor comprising a 120 motor casing, a motor concentrically mounted therein, one end of the motor shaft being provided with a pulley for driving a talking-machine record, the other end of said shaft being provided with a worm, a switch 125 for the circuit of said motor, comprising a pair of spring fingers normally in engagement, a shaft extending through the end of the casing, and in axial alinement with the motor shaft, a train of reduction gearing 130

between the said switch shaft and the motor shaft and embodying a slipping element, an insulation arm fast with the said switch shaft and adapted for interposition between 5 the switch fingers, a dial concentrically disposed on the outside of the end of the casting, and an index finger carried by said

switch shaft for registering with the dial and indicating the position of the insulation arm.

In witness whereof, I have hereunto signed my name.

WILLIAM GENTRY SHELTON.
